(57) **CLAIM**

The ornamental design for a vacuum cleaner, as shown and described.

DESCRIPTION

FIG. 1 is a front view of a vacuum cleaner showing the claimed design;

FIG. 2 is a rear view of the vacuum cleaner of FIG. 1;

FIG. 3 is a top view of the vacuum cleaner of FIG. 1;

FIG. 4 is a bottom view of the vacuum cleaner of FIG. 1;

FIG. 5 is a right view of the vacuum cleaner of FIG. 1;

FIG. 6 is a left view of the vacuum cleaner of FIG. 1;

FIG. 7 is a perspective front, top, right of the vacuum cleaner of FIG. 1;

FIG. 8 is a perspective front, top, left of the vacuum cleaner of FIG. 1;

FIG. 9 is a perspective rear, top, right of the vacuum cleaner of FIG. 1;

FIG. 10 is a perspective rear, top, left of the vacuum cleaner of FIG. 1;

FIG. 11 is a perspective front, bottom, right of the vacuum cleaner of FIG. 1;

FIG. 12 is a perspective front, bottom, left of the vacuum cleaner of FIG. 1;

FIG. 13 is a perspective rear, bottom, right of the vacuum cleaner of FIG. 1; and,

FIG. 14 is a perspective rear, bottom, left of the vacuum cleaner of FIG. 1.
